FIG. 1

FIG. 2

FIG. 5

FIG. 3

FIG. 4

FIG. 6

FIG. 1 is a perspective view of a combined vehicle headrest and protective pad showing my new design;

FIG. 2 is a left side elevational view thereof, the right side elevational view being a mirror image and therefore omitted for brevity;

FIG. 3 is a rear elevational view thereof;

FIG. 4 is a front elevational view thereof;

FIG. 5 is a top plan view thereof; and

FIG. 6 is a bottom plan view thereof.

This application is a divisional application of my co-pending design patent application for Head Rest Structure, Ser. No. D. 12,957, filed July 30, 1968.

I claim:

The ornamental design for a combined vehicle headrest and protective pad, substantially as shown and described.
